(57) **CLAIM**

The ornamental design for a watering can as shown and described.

DESCRIPTION

FIG. 1 is a right elevational view of a watering can according to a first embodiment;

FIG. 2 is a left elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a rear and upper perspective view thereof;

FIG. 8 is a bottom and lower perspective view thereof;

FIG. 9 is a right elevational view of a watering can according to a second embodiment;

FIG. 10 is a left elevational view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a rear and upper perspective view thereof, and,

FIG. 16 is a bottom and lower perspective view thereof.

The broken lines and the half-tone area within the broken lines depict portions of the watering can that form no part of the claimed design.

1 Claim, 8 Drawing Sheets
